CLAIM

The ornamental design for magnifying glasses housing, as shown and described.

DESCRIPTION

FIG. 1 is a front perspective view of an embodiment of a magnifying glass housing;

FIG. 2 is a rear perspective view of the magnifying glass housing of FIG. 1;

FIG. 3 is a side elevational view of the magnifying glass housing of FIG. 1;

FIG. 4 is a rear elevational view of the magnifying glass housing of FIG. 1;

FIG. 5 is a top view of the magnifying glass housing of FIG. 1; and,

FIG. 6 is a front elevational view of the magnifying glass housing of FIG. 1.
